Thomas Head & Son, Jr., Citizens of
Letters Patent.

The Schedule referred to in these Letters Patent, and making part of the same, containing a description in the words of the said Thomas Head & Son, Jr., of their improvement in the mode of raising, straightening, & laying the nap on woollen cloths, & cloths on which a nap is commonly raised by teasing.

To all to whom these presents shall come, we Thomas Head, of the city of New York, in the county and state of New York, and these, Jr., of Lowell in the county of Middlesex, and state of Massachusetts, send Greeting. Be it known that we the said Thomas Head and these Jr., have invented, constructed, made and applied to use, an new and useful improvement in the mode of raising straightening and laying the nap on woollen cloths and cloths on which a nap is commonly raised by teasing which invention and the principles thereof and the mode in which we have contemplated the application thereof and the manner of using and purpose of compounding the same are described as follows, that is to say. It is best that the operation should be performed upon the cloth whilst it is heated with steam or hot air and stretched so as to make it straight, free from wrinkles and wrinkles, when it is to be teased which teasing is to be done with pointed metallic wires or pins set and fixed compactly together, or very nearly so, and parallel with each other having the points all one way and upon the circumference of the same circle or upon the same plane having regard to the intended use of them whether upon a cylinder or a plane. These metallic pointed wires, pins, or points, thus set and fixed compactly or closely together to each other, being very numerous can be made to act upon many points of the cloth at once, will serve as guides and other requisites a light touch and pressure of the cloth upon them while the operation is going on in order to accomplish the work without taking a hold of the cloth

done

so as to injure it and may be made to point slightly up on the cloth to
and raise an uniform crop upon it with much more facility and
expeditiousness and in a better manner than a crop can be raised upon
cloth by cards, teasels or any other mode or means hitherto in use.
These points ought in general to be equal to each other as those of
pointed brass numbered twenty two when set compactly together
or very nearly so in order to operate with the most advantages
by, they may however be set a little nearer or farther apart according to
the kind and quality of cloth or of crop of the cloth to be operated
upon. These pointed metallic wires, pins, or metallic points may be made
or formed of brass or other metal of about the same hardness or harder
than metal sufficiently hard and tough will answer the purpose but
this metal is deemed preferable as not being liable to rust, and being
deemed sufficiently hard. When these pointed metallic wires or pins
are to be put in frames as herein after mentioned, brass wires numbered
twenty two cut into pieces of about three fourths of an inch
long, and pointed nearly like the common brads, but with a point
a little more tapering will answer best, but the common brad pin of
ordinary size with the head removed will answer the purpose tolerably
well. But if these pointed metallic wires or pins are to be set in holes
perforated or made in metallic plates plates as herein after mentioned,
the wires ought to be much smaller. They may be so small that the end
of the wire will require but very little sharpening to bring it to a point
or so that the end may serve for a point, and if the holes in the plate be
made very near to each other these very small wires or pins when
inserted as herein after mentioned being so numerous and near
together will be sufficiently stiff. These pointed metallic wires
pins, or metallic points may be set or fixed upon a plane to be used
as shown in the or upon a revolving cylinder. The best mode of opera-
ting with them is when set or fixed upon a cylinder. The cylinder
may be made of brass or other metal of about the same hardness
but less and may be made hollow so as to contain steam or hot air
which it should be heated so as to heat the points and keep them

Introducing operation of teasing is going on and aid in the process of raising flax, spinning and laying them up as well as in expelling the flax or some produced by friction which have a tendency to lodge between the points. The steam which may be sent into the base of the cylinder through a tube going into the end of the tube or neck of the cylinder and from thence into the base. But heat may be applied to the points by means of a shell connected with a box into which steam or hot air can be admitted and partly encircling the cylinder upon which the points are set or fixed so that the points may be heated by revolving in the shell. They should be heated in order to operate best with them. The operation of teasing with these points however may be performed to a sufficient without heating the points by heating the cloth by steam to be sent into a tube passing under the cloth just before and near the cylinder and having a slit in it from whence the steam can be made to issue up and strike upon and heat the cloth as well as wet it. and it is best to apply the steam in this way as well as to heat the cylinders as before described. Cloth may nevertheless be teased without either the heating of the cylinders or the application of steam as before described, but these are deemed advantageous in the operation. The metallic points or pins may be set or fixed upon the cylinder in various ways. The pointed trap wires or pins may be fixed in a metallic oblong frame of the length of the cylinder made of brass, copper or iron encompassing a space to be filled with the pins of the width of one half of an inch more or less according to the size of the cylinder and as long as the widest cloths intended to be teased. These pointed traps or pins must be filled into the spaces encompassed by the frame compactly and parallel with each other, and crowded so tightly together with the points all one way until the spaces are filled so as to form a solid compact mass as may be needed so that the pins shall project not be about three sixteenths of an inch or a little more above the outer surface of the metallic frame, and so that the points shall form a smooth surface, corresponding with the circumference of the cylinder, or of about the same consistency.

This

When any leaden wire is put into the furnace by means of a pair of tongs with the points down and in a conical and hollowed shape and of an appropriate conicity placed inside the furnace, the size of the iron frame should be about three fourths of an inch deep and about four thirty seconds of an inch wide or so wide that the frame shall be of sufficient firmness and strength. When a sufficient number of pointed wires or pins after they have been twisted and curved tightly into the frame, should be allowed to cool down to the furnace, which may be done while the points are resting on the iron, and will remain solid so as to cause them firmly together and to the frame. The pointed wires are more easily soldered when turned or prepared like the common pins, and in order to prevent the solder from running down to the points, moist clay may be laid in the bottom of the mould about one quarter of an inch deep or of a similar depth in which is laid a flat and soft, the points are to be set and the clay should then be sufficient to become dry and hard, after which and just before pouring the solder upon the blunt ends of the pointed wires they should be heated by placing them which is set by a fire and the solder should be poured upon them whilst they remain hot. The furnace thus filled with the pointed metallic wires or pins as just and cooled may be laid upon the convex surface of the cylinder upon which they are to be used in the form of bags with the points outward and fastened firmly to the cylinder by screws through the frame at the ends and in the middle of these of the furnace otherwise. The whole convex surface of the cylinder must then be covered with these firmly fixed and fastened to it and filled with pointed metallic wires or pins so as to cover every part of the convex surface of the cylinder and to prevent a surface of point left as completely as possible together excepting the spaces occupied by the metallic wires within which the pointed metallic wires or pins are to be set. The pointed wires or pins may be fixed and held firmly together in the form of many rows by a number of points in every point of which a pointed wire or left over together with sufficient pointed wires to be covered by fastening the pointed metallic wires or pins on the cylinder.

1140

to be used is by making two plates of suitable width and length corresponding with the length and concavity of the cylinder and perforating, punching or making holes in these plates, similar to each other as may be and leave enough of plate to hold the pins just long enough to admit the blunt ends of the pointed metallic wires or pins. In these holes pointed metallic or of wires numbered about twenty eight more or less, or steel wires of a much smaller size, or of a size much smaller than the pins used for filling the frame as before mentioned and about three eighths of an inch long or a little more or less according to the thickness of the plate which may be of the thickness of about numbered twenty three or what is commonly called twenty four once copper more or less if the plates be of that metal should be inserted so that the blunt ends may be even with the under surface of the plates, and the points must be graduated by a concave mould so as to conform to the surface of the cylinder on which they are to be used. These pointed metallic wires or pins thus set in the plates may be soldered to the plate on the side opposite to the points with common solder by means of a mould attached thereto so that the solder can be poured in between the plate and the mould sufficient in quantity to secure the points to the plate and to each other. These plates thus prepared and filled with pointed wires or pins must be laid on the concave surface of the cylinder with the points outward and secured firmly to it by screws or otherwise until the concave surface of the cylinder is covered with the plates. When a cylinder with metallic points is intended only for smoothing and laying the surf. The points may be set and fixed in either of the modes above described at such an angle with the circumference of the cylinder as in the operation to have little or no action upon the sides of the surf but to smooth and lay the surf. The cylinders upon which the pointed metallic wires points or pins are set and fixed in any of the modes above mentioned may be driven or turned round with great velocity in the process of laying straightening and laying the surf by the power of steam or air etc.

by connecting the cylinder which is to be fixed in a frame with its
to a drum, and the cloth while passing over the cylinder should be made
to touch the points lightly and its pressure upon the points may be
graduated by a roller near the cylinder over which it passes connected
with a hatchet so that the roller may be raised or lowered as an
occasion may require. The cloth may be stretched upon rollers
in any of the various modes now in use while it is made to pass
over the cylinders. When the pointed metallic wires are to be
used upon a plane as hand jacks or otherwise they may be
set in either of the modes above mentioned excepting that the points
in this case ought to be even with each other or in the same plane.
When the operation is to be performed by points set or made upon
cylinder a revolving cylinder brush having a motion contrary to the
cylinder containing the points, should be so fixed as to be in contact
with the points on that cylinder in order to assist in clearing the
flocks or down from between the points. Harnesses and cloths
of a similar kind may be stretched and made to pass over the cylin-
der in the following manner. The two ends of the cloth in the process
of teasing should be sewed or connected together and the cloth
should be made to pass alternately over and under revolving rollers
fixed in a frame sufficient in number to take up the whole of the
cloth so that no part of it may hang loose and so that it may
pass over the cylinder in which the points are and that the
surface on which a nap is to be raised straightened and laid
may be made to touch the points lightly as it passes over the
cylinder. And one of the revolving rollers next to the cylinder shall
be so fixed in a movable frame set in grooves that by means of
handles and hatchets before mentioned the frame may be raised
or lowered and with it the roller set in it so as to let the surface of
the cloth to be teased down upon the points, or raise it and grad-
uate the action or friction of the points upon the cloth at the dis-
cretion of the operator. The cloth, during the operation of raising
straightening and laying the nap should be stretched and kept
tensioned.

stretched lengthwise so as to make the surface of the cloth on which the nap is to be raised as straight even and free from wrinkles as possible, which may be done by having one of the revolving rollers under which the cloth passes fixed in a movable frame made to slide in a groove or mortise through the posts in the main frame capable of being moved up and down, at the two ends of which frame weights of sufficient magnitude stretch the cloth and to be suspended upon hooks to be fixed upon this frame. The cloth should also be stretched widthwise which may be done with the hand or any other convenient way. A rotary motion is given to the cloth by the revolving of the rollers over and under which it passes and is stretched and which causes it to pass over the cylinder in which the metallic points are set and fixed. But satinette and cloths of that kind may be better stretched in the modes now in common use. The description above given may be better understood by reference to the plans hereto annexed marked A, B, C, and the explanation thereof which is as follows: That is to say, Plan A exhibits a side elevation and an end elevation of the frame in which the metallic cylinder with points the cylindrical brush and the rollers over and under which the cloth passes are set. Plan B, exhibits also a side elevation of the frame with a view of the pulleys, ratchets, a section of the brush, a section of the metallic cylinder with points one of the metallic frames in which the points are to be set and the movable frame containing a roller with the hooks attached to the base from which the weights to stretch the cloth are suspended.

Plan C, exhibits a view of the frame with the metallic cylinder, cylindrical brush and rollers set in it. A and A, are lines which represent the cloth with the two ends connected stretchers and passing by a rotary motion over and under the rollers and over the cylinder in which the metallic points are set and fixed while the cylinder is revolving with great velocity. A represents a hollow metallic cylinder in which the metallic points

points are set and fixed and which cylinder being set in the frame may be driven by the force of steam or water or otherwise being turned by means of a belt passing over a driving pulley connected with the hub at one end of the cylinder so as to communicate motion from a revolving drum. C represents a revolving cylindrical brush set also in the frame and in contact with the staple points which are upon the revolving metallic cylinder and having a driving pulley connected by a cross belt with a pulley at the end of the cylinder so as to give the brush a motion in a direction contrary to the motion of the cylinder for the purpose of clearing the down or flocks from between the points & represents a groove or mortise through the posts in the main frame for the movable frame to slide in to which the weights for stretching the cloth are hung and where is a roller under which the cloth passes is set. E represents the moveable frame sliding in the groove or mortised for raising the roller h' to different heights & represents a double pulley with which belts are to be connected for giving motion to the rollers by means of gear & represents a single pulley for the like purpose and by means of a belt to connect the motion of the upper and lower rollers h' represents the roller set in the moveable frame under which roller the cloth passes and is stretched by means of weights suspended to hooks fastened in each end of the frame. iiiiiii represent third gear or cog wheels to regulate the motion of the rollers so that they may move in one and the same direction. jjjjj represent no braces to the frame in which the rollers cylindrical brush and metallic cylinder are set. kk represent the axis of the pulley with gear for giving motion to the rollers. mmmmmmmmm represent rollers over or under which the cloth passes and from which it receives its motion. n represents a shifting roller set and used in any part of the frame as the different lengths of the cloths may give occasion. o represents the roller set in a moveable frame for letting the cloth down upon the points set.

set and fixed on the metallic cylinder or raising it, or represent the hand and notches for raising and lowering the roller on over which the cloth passes whereby its touch and pressure upon the points on the metallic cylinder may be graduated. P.P.P.P. represent principal parts of the main frame, 1 represents the driving pulley to the metallic cylinder, 2 represents the small pulley for the band to play upon to turn the cylindrical brush, 3 represents a small pulley at one end of the metallic cylinder connected by a band to the pulley at one end of the brush so as to turn the brush in a direction contrary to that in which the cylinder moves. 4 represents the hooks attached to the moveable frame from which the weights are suspended. 5 represents a platform for the workman to stand upon. From these plans and the above description it is believed that the mode of operating in teasing cloth or which is deemed best with the points set and fixed as before mentioned may be easily understood. In general it is best that the cloth to be teased should be wet at the time of teasing it. The operation however may be performed in various ways with or without the application of heat or steam, and the cloth may be treated while the operation of teasing is going on by various other means than those above described. The size and length of the wires whether set or fixed in frames, or in or upon metallic plates or a metallic substance may be varied at discretion and whether in or upon metallic plates, or a metallic substance these wires may be so small that the ends will come as points with little or no sharpening, and these metallic wires pins or points may be set and fixed neatly together in any way in which they can be secured firmly in their places and may be used on a plane or upon a cylindrical surface, and if they happen on a cylinder in frames or plates this cylinder may be hollow or solid and of metal or wood if it be of sufficient strength and the size of the cylinder may be varied at discretion, and as metallic wires

where set and fixed in the manner of the common cards in both
or placed at a considerable distance from each other upon a frame
upon a cylindrical surface have hitherto been used for the
purpose of teasing and raising a nap upon cloth, it is to be es-
sentially understood that wires or set, and such cards and the
setting or fixing of wires or pins in such manner as last for wire or
any wire in which they have hitherto been set and used for the
purpose aforesaid, is not claimed as a new invention. The chief
advantage arising from our invention consisting in the setting and
fixing of pointed metallic wires pins or points or wires or pins so
small that the ends may serve for points with little or no sharpening
in a firm manner in frames or in or upon metallic plates or in
or upon a metallic substance or any substance in or upon which
they may be so set and fixed with sufficient firmness compactly,
closely or very nearly together, and so close to each other than
they have hitherto been placed set or fixed on any such cloth
in leather felt or otherwise so that the points may the better
serve as gages to each other, act upon many points of the cloth
at once require but a light touch or pressure of the cloth upon
them in order to accomplish the work and without taking such
hold upon the cloth as to injure it raise a nap uniformly
thereon with much more facility and expedition and in a better
manner than can be done by the cards or needles aforesaid or
any mode or means hitherto in use. And notwithstanding that
we have mentioned and recommended the application of heat or
steam & water in the operation, and described a mode of operating
and machinery which is deemed advantageous in the use of our
invention but which may be used or not or varied at the
discretion of the mechanic or operator and which a mechanic
of ordinary skill will readily understand, we hereby nevertheless
explictly declare that what is claimed by us as a new
invention and improvement, and all which in the said card
and the claim herein as to original invention and improvement
is the

X6045
1449

in the setting, placing or fixing of metallic wires, pins or
points, and wires to small but the ordinary wire for points
with little or no sharpness compactly closely or very near to each
other in metallic frames or any frames of sufficient strength and
durability or in or upon metallic plates or in or upon a metallic
substance or any substance in or upon which they may be so
set and fixed with sufficient firmness upon a place or upon
surface for the purpose of being used when so set fixed made
or placed firmly and near to each other as aforesaid for tearing
and raising straightening and laying the nap upon woollen
cloth and cloths upon which a nap is usually raised by tearing
and cominck and such facts and no more of the instrumental
machines above described and of any instrument or machine
for tearing cloths as is constituted by or composed of metallic wires
pins or points so set placed or fixed firmly in metallic
frames or in or upon metallic plates or in or upon a metallic
or other substance compactly closely or near to each other
as aforesaid.

In witness whereof we the said Thomas
Hurd, and Jesse Fox, have hereunto set our hands and
seals this twenty seventh day of October in the year of our
Lord one thousand eight hundred and thirty.
